TOBACCO FEED BELT FOR CIGARETTE MACHINES

Filed Oct. 28, 1930

FIG. 3

UNITED STATES PATENT OFFICE

ARTHUR PODMORE, OF LONDON, ENGLAND, ASSIGNOR TO AMERICAN MACHINE & GI
FOUNDRY COMPANY, A CORPORATION OF NEW JERSEY

TOBACCO-FEED BELT FOR CIGARETTE MACHINES

Application filed October 28, 1930. Serial No. 491,755.

This invention relates to tobacco feeds for continuous rod cigarette machines and is an improvement on the tobacco feed forming the subject matter of my prior application, Serial No. 387,686, filed August 22, 1929. The main object of the invention is the production of an improved tobacco feed including a carded belt which is supported on the pitch lines of the chains carrying the same. With this and other objects not specifically mentioned in view, the invention consists in certain constructions and combinations which will be hereinafter fully described and then specifically set forth in the claims hereunto appended.

In the accompanying drawing which forms a part of this specification and in which like characters of reference indicate the same or like parts:

20 Fig. 1 is a sectional side elevation of a portion of the improved tobacco feed;

Fig. 2 is a sectional view taken on the line 2—2 of Fig. 1; and

Fig. 3 is a detail view of the carded belt.

25 In carrying the invention into effect, there is provided a tobacco hopper, a feed drum in said hopper, a carded belt forming the floor of said hopper, spaced chains for driving the belt toward said feed drum, and connections 30 between said belt and chains for supporting the belt on the pitch lines of the chains. In the best constructions contemplated, said connections include brackets secured to the cross pins of said chains and cross bars secured to said brackets and carrying the carded belt in the pitch lines of said chains. In the preferred form of the invention, said carded belt is formed of a plurality of longitudinally extending carded strips secured directly to said

35 cross bars. These various means and parts may be widely varied in construction within the scope of the claims, for the particular device selected to illustrate the invention is but one of many possible concrete embodiments

40 of the same. The invention, therefore, is not to be restricted to the specific construction shown and described.

45 Referring to the drawing, the tobacco in the hopper 10 rests on the carded belt 148 which forms the floor of the hopper and is

intermittently moved, as hereinafter described, in the direction of the arrow shown in Fig. 1. The carded belt is formed of a series of longitudinally extending carded strips which are secured directly to the cross bars 149 which are fixed to brackets herein-after described carried by the cross pins of the transversely spaced chains 150 threaded over the sprockets 151 on the shafts 152 and 153 which are supported by the frames 154 and 155. A crank 156 on the shaft 157, which is supported in the frames 154 and 155 and provided with a spiral gear 158, is operated by a spiral gear 159 on the shaft 160 meshing with the gear 158. The shaft 160 is driven from the main shaft by any suitable means, not shown. A rod 164 connects the crank to a lever 165 which is pivoted on the shaft 153 and provided with a pawl 166 engaging the ratchet 167 to intermittently move the chains 150 and carded belt 148.

50 The brackets 168 on the cross pins 169 of the chains 150 have the cross bars 149 secured thereto inside the pitch line of the chains, so that the cross bars may support the carded belt on the pitch lines of the chains, as shown in Fig. 3, with the pitch line PL lying throughout its length in the median plane of the belt. By this construction, the path of the belt between the sprockets coincides 55 with the pitch lines of the chains on their respective sprockets, thereby avoiding the excessive stretching of the belt which would result if the belt were supported outside the pitch lines of the chains and the production 60 of slack and wrinkles in the belt which would result if it were supported inside the pitch lines of the chains.

65 The tobacco is removed from the carded belt as it is fed to the feed drum 17 on the shaft 52 and carried from the feed drum to the cigarette machine by suitable means, not shown.

70 In view of the foregoing, a detailed description of the operation of the device is 75 deemed unnecessary and accordingly omitted in the interest of brevity.

I claim:

75 1. In a cigarette machine feed, the combination with a hopper, of a feed drum therein, 80

a carded belt forming the floor of said hopper, transversely spaced chains for positively driving said belt toward the drum, and connections between said belt and chains for supporting the belt on the pitch lines of the chains.

2. In a cigarette machine feed, the combination with a hopper, of a feed drum therein, a carded belt forming the floor of said hopper, transversely spaced chains for positively driving said belt toward the drum, and connections between said belt and chains for supporting the belt on the pitch lines of the chains, said connections including cross bars carrying the belt and secured to the chains inside the pitch line thereof.

3. In a cigarette machine feed, the combination with a hopper, of a feed drum therein, a carded belt forming the floor of said hopper, transversely spaced chains for positively driving said belt toward the drum, and connections between said belt and chains for supporting the belt on the pitch lines of the chains, said connections including brackets secured to the cross pins of the chains, cross bars carrying the belt secured to said brackets.

4. In a cigarette machine feed, the combination with a hopper, of tobacco feeding means therein, and a moving floor for said hopper comprising an endless series of cross bars laid close together having longitudinally extending carded strips secured directly to said cross bars, and means connected to said cross bars for driving the belt toward said feeding means.

In testimony whereof, I have signed my name to this specification.

ARTHUR PODMORE.
